United States Patent

Des. 241,485
Patented Sept. 21, 1976

241,485

COMBINED SEAT, TABLE, PLANTER AND MULTIPLE BENCH UNIT OR SIMILAR ARTICLE

Leif Blodee, Holland, Mich., assignor to
The Gunlocke Company, Wayland, N.Y.

Filed July 1, 1974, Ser. No. 484,806

Term of patent 14 years

Int. Cl. D6—05

U.S. Cl. D6—4

FIG. 1 is a view in perspective of a combined seat, table, planter and multiple bench unit or similar article in accordance with the invention; and

FIG. 2 is a perspective view of the combined seat, table, planter and multiple bench unit or similar article of FIG. 1 as seen from the opposite side.

I claim:

The ornamental design for a combined seat, table, planter and multiple bench unit or similar article, as shown and described.
